UNITED STATES PATENT OFFICE.

JOHN DE VOGEL, OF PATERSON, NEW JERSEY.

REEL.

Application filed January 12, 1927. Serial No. 160,633.

This invention relates to reels and particularly to reels on which to wind cloth or other sheet material in flat form. When the material has been wound up on such a reel 5 it is desirable that the reel should be collapsible so that the bolt of material may be readily removed therefrom. Therefore my object is to provide a reel of this class which, while it is adapted to be so supported in a 10 suitable frame that it may be rotated in performing the winding operation, is also adapted to be readily collapsed by the attendant when the bolt has been completely wound and is to be removed, though secured against 15 such collapse while the winding operation is going on.

To these ends the reel includes a pair of elongated longitudinal members around which the material to be bolted is wound and 20 having one such member shiftable back and forth relatively to the other in an arc in a plane extending radially from the axis of the reel, said reel also including means to temporarily hold and preferably positively 25 lock said member in that position in which it is relatively remote from said axis; this means is preferably located at the end of the reel so as to be readily accessible.

In the present example herein shown and 30 described there are two members shiftable as described; but so long as one is shiftable and adapted to be temporarily held as stated my invention will be carried out.

In the drawing, which shows the preferred 35 form,

Fig. 1 is an edge view of the reel;

Fig. 2 is a side view thereof;

Fig. 3 is a fragmentary side elevation on 40 a larger scale and partly in section; and

Fig. 4 is an end view.

The two shiftable and elongated or blade members are indicated at 1 and may be suitable slats of wood. A third member is a metallic shaft 2 which has its ends turned down 45 to form axial bearings 3. The three members are in the same plane and in the present example all parallel with each other and remain in that relation in the collapsed and expanded conditions of the reel.

Links are indicated at 4 and may be short 50 flat lengths of metal. In the present instance there are three of them, one at the middle and the other two at the ends of the members 1 and 2. They are pivoted to said members at 5, i. e., to the member 2 at the middle of each link and to the other two members

at the ends of each link. Preferably for the accommodation of each link the member 2 is formed with a slot 6 and for a similar purpose each member 1 is formed with a recess 60 or groove 8 which receives the end of such link; since the narrow surfaces of the members 1 are presented to the member 2 these grooves are formed in such surfaces.

The members 2 may each shift back and 65 forth in an arc from the position shown by full lines in the drawing (in which condition the reel is expanded) inwardly toward each other, or toward member 2, a preferably limited distance; this is determined by the 70 contact of one of the links with one end of the corresponding slot 6. For limiting the movement of the members 2 in the opposite direction a stop 9 may be brazed or otherwise secured to the member 2 across one of 75 the slots in position to be engaged by the corresponding link.

The locking device for holding the parts 80 in that position in which the reel is expanded is as follows: A socket 10 may be screwed into or otherwise secured to member 2. This receives a bolt 11 having a pin 11^a received by an L-shaped slot 12 in the socket and also having a reduced extension or lug 11^b. The bolt is normally pressed outward by a spring 13 contained in the socket and interposed between the bolt and the inner end of the 85 socket. The stem of the bolt protrudes through member 2 and has a knob 14. This locking device projects in the plane occupied by the three members 1 and 2 and when the reel is expanded a hole 15^a in a keeper plate 15 on one of the members 2 is positioned so as to receive and afford a detent shoulder to be engaged by the lug 11^b of the bolt, thus 90 locking the members 2 in the expanded relation. In order to collapse the reel the attendant withdraws the bolt to clear the keeper plate, locking the bolt in retracted position by turning it until its lug 11^a engages the 95 offset portion of slot 12 in the socket.

I place the locking device at the end of the reel not only so that it may be conveniently reached but so that when the member 2 having the keeper is shifted one way or the other 100 it will clear the socket.

When the reel is in use it is placed, in expanded condition, in its bearings in the frame of the winding-up machine and then rotated to wind thereon and thus form the 110 bolt of cloth or other sheet material. When the winding is completed the attendant re-

moves the reel and, having released the locking device, presses the two members 2 together to collapse the reel so that it may be readily slipped from the bolt.

Having thus fully described my invention what I claim and desire to secure by Letters Patent is:

1. A reel including a supporting member having axial bearings for the reel, a blade member extending substantially parallel with the axis of the reel, links spaced from each other lengthwise of said members and each pivoted to each member to move pivotally in a plane extending radially from said axis, and means on one member and engageable with the other member to temporarily lock the system of parts including said members and the links in that relation to each other in which the blade member is relatively remote from said axis.
2. A reel including a supporting member having axial bearings for the reel, a blade member extending substantially parallel with the axis of the reel, links spaced from each other lengthwise of said members and each pivoted to each member to move pivotally in a plane extending radially from said axis, a locking device on one member and a detent shoulder on the other member arranged to be engaged by the locking device when the blade member is relatively remote from said axis.

totally in a plane extending radially from said axis, a locking device on one member and a detent shoulder on the other member arranged to be engaged by the locking device when the blade member is relatively remote from said axis.

3. A reel including a pair of spaced elongated, longitudinal members around which the material to be bolted is wound and having one such member shiftable toward and from the other in an arc in a plane extending radially from the axis of the reel, a socket projecting in said plane from said other member near one end thereof and arranged to be radially opposed by the first member when the latter is in a position in which it is relatively remote from the other member and to be cleared by the first member in the shifting thereof, and a bolt movable radially in said socket into and out of locking engagement with the first member when in said position.

In testimony whereof I affix my signature.

JOHN DE VOGEL.
